RECORDING MECHANISM

Fritz Loeffler, New York, N. Y.

Application July 16, 1937, Serial No. 153,880

4 Claims. (Cl. 271—2.3)

This invention relates to new and useful improvements in recording mechanism, and particularly to recording mechanisms in which the record is made on a web of paper continuously moved by a clock mechanism.

The object of the invention is to provide a device which may be readily and accurately adjusted without introducing undue complications.

With this object in view I provide certain improved instrumentalities, of which the following are noted:

The gear train through which the clock mechanism drives the recording web is arranged for ready adjustment to eliminate backlash; means are provided to eliminate play in the driving roll of the recording web; means are provided to compensate for manufacturing irregularities in the construction and mounting of the supporting brackets of the driving, guiding and take-off rollers.

These and other features of the invention will more clearly appear from a preferred embodiment thereof which will be described with the aid of the drawing in which—

Fig. 1 is a side elevation of as much of the recording mechanism as is necessary for a clear understanding of the present invention;

Fig. 2 is a front elevation of the same;

Fig. 3 is a fragmentary illustration of the gearing;

Figs. 4, 5 and 6 are detailed views of the mounting of one of the rollers; and

Fig. 7 is a cross-section along line 7—7 of Fig. 1.

The mechanism is mounted on a base plate 1. The clock mechanism, the details of which are not shown, is within a casing 2 fastened to the base plate.

The record is made on the usual paper web 10, a supply of which is mounted on a roller 3. One pin 4 of the roller is journaled in a side wall of the casing 2, and the opposite pin 5 engages a leaf spring 6 mounted on a forked bracket 7. The bracket 7 has a foot 8 which is fastened to the base plate 1 by means of two screws 9. The roller 3 as well as the two other rollers 12 and 13 over which the paper 10 passes, must be accurately positioned because otherwise the record, as related to the time markings of the paper, will be inaccurate. The smallest deviation of a roller axis from the desired position may result in substantial inaccuracy of the record. To make possible the exact positioning of the relatively crudely made rollers, the following arrangement is provided:

To insure accurate positioning of the bracket 7 and to compensate for manufacturing inaccuracies, a screw-threaded stud 11 is driven through the base plate 1 and engages the bottom of the foot 8 between the screws 9. By means of the two screws 9 and the screw-threaded stud 11, accurate positioning of the bracket and therefore the roller 3 is insured. Bracket 46, supporting one end of roller 13, is similarly mounted. As best shown in Fig. 7, the screw 10 11a engages the foot of the bracket in alignment with the bracket proper, whereby adjustment of the bracket in all directions is made possible; within the obvious limitations of the structure, the bracket can be swung into any angular position with respect to its axis and firmly held in such position.

The web 10 is led from the roller 3 onto driving roller 12 and thence over an aluminum table 12a onto the take-off roller 13.

The driving roller 12 is mounted on a shaft 14 which projects through the two walls of the casing 2 and has frictionally held against its end a gear wheel 15 by means of a thumb nut 16 screwed on the screw-threaded projecting end 17 of the shaft.

The other end of the shaft 14 is supported in a bracket 20, a foot 21 of which is held against the base plate 1 by means of screws 22. To insure accurate positioning and to guard against wear and end play of shaft 14, its bearing surface is not directly in the bracket 20 but in a bearing 23 which is screwed into the bracket 20 and through which projects the narrowed end 24 of shaft 14. The bearing 23 engages the shoulder formed by the shaft 14 and prevents end play.

The roller 12 is driven by motive power supplied from two clock springs (not shown) in casing 2 and which may be wound up by means of square-shouldered shafts 25 and 26, respectively. The clock mechanism is regulated by the usual escapement device (not shown), the shaft of which projects through the housing 2 and has fastened to its screw-threaded end 27 by means of a knurled thumb screw 28, a gear wheel 29. Power is transmitted to the shaft 14 through gears 29, 30, 31 and 15. It will be noted that the gears 30, 31 which couple the gear 29 to gear 15 do not have their centers in alignment with the centers of gears 15 and 29. Furthermore, the two gears 30 and 31 are not mounted on the side wall of casing 2. These two gears are mounted by means of screws 32 and 33, respectively, on mounting plates 34 and 35, respectively.

These mounting plates are fastened to the side wall of casing 2 by screws projecting through two relatively large holes indicated in each mounting plate. By holding in place these 5 mounting plates by means of screws which loosely fit within the holes of the mounting plates, and by having the mounting plates project beyond the circumference of the gears 30 and 31, the positioning of the mounting plates and, 10 therefore, of the gears, can be readily varied and thus all backlash in the gearing taken up. Since the gears cover the screws which pass through the holes in the mounting plates, the latter cannot be tampered with after adjustment.

15 The table 12 is of aluminum and to insure its rigidity without sacrificing lightness and without preventing ready access to supply spool 3, the end of the table 12 is formed into a triangular rib 40. This rib 40 partly overlies arm 20 41 projecting from and integral with the bracket 20. The arm 41 is bent out of the plane of the bracket 20 and serves as a rigid support of the table 12, to which the rib is fastened with two screws. The opposite edge of the table 12 is bent 25 down and is fastened to the side wall of casing 2.

The web 10 is provided with marginal perforations such as 42 which engage pins 43 projecting from the roller 12. Three pins are equally spaced around the left-hand edge of roller 12 30 and three pins are similarly spaced on the right-hand edge of the roller 12, but staggered with respect to the pins on the left-hand edge. The purpose of this arrangement is to reduce the friction opposing the moving of the web 10 and yet insure engagement of the perforations in one edge or the other of the web by the pins and thus prevent slippage of the web. I have found that instead of the customary arrangement of providing six pins near each edge of the roller 12, three pins provided in each edge will produce the same traction and reduce the resistance offered by the pins to about one half.

The take-off roller 13 has a shaft 45, one end of which is supported in the bracket 46, and the other end is hollowed out as indicated at 47, and has a pin 48 driven through it. Within the hollowed-out portions 47 fits the slotted end 49 of a spring-driven-shaft which will drive shaft 45 through the pin 48. The mechanism (not shown) for driving this shaft is also enclosed 50 within the casing 2 and in the drawing I have shown only the winding stud 50 of this clock mechanism.

It will be seen that once the paper web 10 is positioned with respect to the usual recording stylus (not shown), neither gear back-lash nor roller end-play will disturb the accuracy of the adjustment. It will be further observed that great accuracy of adjustment is possible although the brackets, rollers, gears, etc., are mass

products instead of the types usually encountered in precision instruments.

What I claim is:

1. In combination, a shaft, means including a first gear carried by said shaft and a second gear for driving said shaft, a common plate on which said second gear is mounted and in which said shaft is journaled, a third and a fourth intermeshed gears for coupling said first and second gears, a separate mounting plate for each of said third and fourth gears, the centers of the latter being out of the line connecting the centers of the first and second gears, and means for adjustably mounting said separate mounting plates on the first mentioned plate, whereby close adjustment may be readily effected between each pair of intermeshing gears.

2. In a recording device, a web of paper having perforations along its two margins, a roller for advancing said web having pins along its two edges projecting through the perforations in the web, the pins along one edge being staggered with respect to the pins at the other edge of the roller, a device continuously tending to pull said web of paper away from said roller, means for rotating said roller, said means including a gear fastened to said roller and a second gear, a third gear engaging the first gear, a fourth gear engaging the third and the second gears, a mounting plate for each of said third and fourth gears part of which projects beyond the peripheries of said third and fourth gears, said mounting plates having relatively large apertures for adjustable mounting and which are covered by the gears, the centers of the third and fourth gears being out of alignment with the centers of the first and second gears.

3. In a recording device having a recording web, a roller for advancing said web, mechanism for driving one end of said roller, a shouldered stud projecting from the other end of said roller, a bracket, and an externally screw-threaded bearing in said bracket holding the end of said stud and engaging the shoulder thereon.

4. In a recording device having a supply of recording web, a roller for advancing web from said supply, a table of sheet metal covering said supply and on which the advancing web rests, said table being of substantially the same width as said roller and having one edge turned down, the turned-down edge being tapered towards an end of the table to give rigidity to said table and still permit ready access to said supply, a bracket, a bearing in said bracket for said roller, and a supporting arm for said table projecting from said bracket, said arm being bent into a plane so that the turned-down edge of the table overlies it.
